UNITED STATES PATENT OFFICE

122,133

DESIGN FOR A COMBINED REGISTER SHIELD AND FILTER

Harry A. Bedol, Cleveland, Ohio

Application May 24, 1940, Serial No. 92,576

Term of patent 14 years

To all whom it may concern:

Be it known that I, Harry A. Bedol, a citizen of the United States of America, residing at Cleveland, county of Cuyahoga, and State of Ohio, have invented a new, original, and ornamental Design for a Combined Register Shield and Filter, of which the following is a specification, reference being had to the accompanying drawing, forming part thereof.

Register Shield and Filter showing my new design; and

I claim:

The ornamental design for a combined register shield and filter, as shown and described.

HARRY A. BEDOL.
